United States Patent Office

Des. 187,246
Patented Feb. 16, 1960

187,246

BOTTLE

Rufus K. Barton, Jr., Ladu, Mo., assignor to Barton Manufacturing Company, St. Louis, Mo., a corporation of Missouri

Application September 4, 1959, Serial No. 57,434

Term of patent 14 years

(Cl. D58—8)

FIG. 1.

FIG. 2.

FIG. 3.

I claim:

The ornamental design for a bottle, substantially as shown.
